UNITED STATES PATENT OFFICE.

JAY HUGH JOHNSON, OF KNOXVILLE, TENNESSEE.

GAGE FOR LAYING SHINGLES.

1,366,462.

Specification of Letters Patent. Patented Jan. 25, 1921.

Application filed December 5, 1919. Serial No. 342,760.

To all whom it may concern:

Be it known that I, JAY HUGH JOHNSON, a citizen of the United States, residing at Knoxville, in the county of Knox and State 5 of Tennessee, have invented a new and useful Improvement in Gages for Laying Shingles, of which the following is a specification, reference being had to the accompanying drawing.

10 My improvement relates particularly to a gage structure which is to be applied to a course of shingles already laid and to present a part in proper position to receive against it the lower ends of the next course 15 of shingles.

The object of my invention is to provide such a structure in a form adapted to be easily and effectively attached in the working position and afterward released and 20 again attached. A further object of the invention is to provide a structure which may be built at moderate cost and which, when applied in position to the last course of shingles, will not extend into the working 25 space and thereby offer hindrance to the rapid laying and attaching of shingles for the next course.

In the accompanying drawings,

Figure 1 is a plan of an apparatus embodying my improvement, parts being broken away;

Fig. 2 is a rear elevation of the locking mechanism shown at the left hand end of Fig. 1, parts being broken away;

35 Fig. 3 is an upright section on the line, 3—3, of Fig. 1, looking toward the right;

Fig. 4 is an upright section on the line, 4—4, of Fig. 1, looking in the direction of the arrow;

40 Fig. 5 is a section on the line, 5—5, of Fig. 1, looking in the direction of the arrow.

Referring to said drawings, A, is a bar extending throughout the length of the apparatus. A strip, B, of sheet metal is of the 45 same length as the bar, A, and is bent to form a horizontal part, B¹, resting upon the upper face of the bar, A, and a part, B², extending downward over the forward edge of the bar, A, and a rib, B³, extending forward from the lower edge of the part, B², and adapted to rest upon the shingles of the last course and to constitute a ledge upon which shingles for the next course may rest. This sheet metal strip is secured to the bar, 50 A, by means of bolts, A¹ and A². Near each end of the bar, A, a horizontal U-shape yoke, 55

C, is applied to the bar, A. Said yoke is formed of strap iron arranged in upright planes, excepting that the ends of the yoke are turned into a common horizontal plane 60 and applied against the lower face of the bar, A, and secured by the bolts, A¹, said bolts passing through said ends and said bar and the sheet metal strip, B, and securing the three members to each other. 65

A tongue, D, extends forward beneath the rear part of the yoke and has an upward extension, D¹, overlapping the rear face of the yoke. A bolt, D², extends through an aperture, D³, in the yoke and said extension and 70 binds the latter to the yoke. In the yoke there is another aperture, D⁴, located lower down. If the tongue is to be set lower, the bolt, D², is extended through the lower of said apertures. The forward end of the 75 tongue, D, is made chisel-form, the edge being at the lower face of the tongue. Thus the tongue is adapted to be pushed forward beneath the lower ends of the course of shingles which was last laid. The distance between the upright part, B², of the sheet metal strip, B, and the upward extension of the tongue, D¹, equals the distance between the 80 ends of adjacent courses of shingles, so that when the tongue, D, is pushed beneath the 85 last course of shingles until the lower ends of said shingles bear against the upward extension, D¹, the part, B², of the strip, B, will be in the right position to receive the lower ends of the new course of shingles. 90 When the gage has been put into this position, it is to be secured against movement until after the next course of shingles has been laid and secured in position. The mechanism for securing the gage will now 95 be described.

In each arm of the yoke which is the nearer the middle of the gage there is a horizontal slot, C¹, and attached to the opposite arm of each yoke is a plate, C², which 100 has a similar horizontal slot, C³, said plate being secured to the adjacent arm of the yoke by means of bolts, C⁴. The plate, C², extends above the adjacent yoke arm and the slot, C³, is above the upper edge of said 105 arm. Thus the slot, C³, is higher than the slot, C¹. At each end of the gage a bar, E, extends through the slots, C¹ and C³, of the adjacent yoke and to the middle of the gage. At the middle of the gage a bracket, E¹, is 110 secured to the bar, A, and the sheet metal strip, B, by the bolts, A². A hand lever, E²,

is pivoted to the bracket, E^1 , by means of a bolt, E^3 , the short end of said lever projecting toward the bar, A . One of the bars, E , has its adjacent end coupled to the lever, E^2 , at one side of the pivot of said lever while the other bar, E , has its adjacent end coupled to the hand lever at the opposite side of the pivot. Thus, when the hand lever is turned in the horizontal plane in one direction, the two bars, E , are drawn endwise toward the middle of the gage and when the hand lever is turned in the opposite direction, the bars, E , are moved from each other endwise.

15 Within each yoke, C , a U-shape roller supporting yoke, E^4 , is supported on the bar, E , the arms of the yoke being directed downward. An upright bolt, E^5 , extends through said yoke and the bar, E , and secures 20 the yoke immovably to the bar. Each arm of each yoke has a horizontal bearing, E^6 , in which rests the journal, E^7 , of a roller, E^8 .

On account of the different elevations between the slot, C^1 , and the slot, C^2 , endwise 25 movement of the bars, E , will change the elevations of the rollers, E^8 , the rollers being forced downward when the bars, E , are moved toward the middle of the gage and the rollers being raised when the bars, 30 E , are moved in the opposite direction.

The operation of the apparatus is as follows:

The long end of the hand lever, E^2 , having been pushed to the left, whereby the 35 bars, E , are put into their outer positions and the rollers, E^8 , are put into the raised positions, the gage is applied to the last laid course of shingles, the tongues, D , being pushed under the lower end of the shingles 40 until said ends bear against the upward extension, D^1 , of said tongue. Then the hand lever, E^2 , is shifted rightward until the rollers, E^8 , bear firmly upon the shingles which rest upon the tongues, D . By this 45 means the gage is secured in its new and working position.

It is to be observed that the faces of the rollers, E^8 , are not dragged over the faces of the shingles, but that the rollers in their 50 traverse make a rolling contact with the faces of the shingles. Thus injury to the shingles by the clamping of the gage thereto is avoided.

When the gage has been put into position, 55 the shingles for the next course are laid on the ledge, B^3 , with their lower ends resting against the part, B^2 . The ledge prevents the loose shingles from slipping under the gage.

60 It is to be noted that for convenient operation, the gage is to be five or six or more feet long, and that, notwithstanding this length, the gage can be put into position by a single forward movement of the entire

gage and a single sidewise movement of the 65 hand lever.

I claim as my invention,

1. In an apparatus of the nature described, the combination of an elongated member presenting an edge against which the ends 70 of shingles may be laid, clamping mechanism attached to said member and comprising a tongue adapted to extend beneath a laid course of shingles and a roller located above the tongue and adapted to be moved 75 bodily to different elevations, substantially as described.

2. In an apparatus of the nature described, the combination of an elongated member presenting an edge against which the 80 ends of shingles may be laid, clamping mechanism attached to said member and comprising a tongue adapted to extend beneath a laid course of shingles, a roller located above the tongue, and a roller support held 85 for shifting in a path inclined to the upper face of the tongue, substantially as described.

3. In an apparatus of the nature described, the combination of an elongated 90 member presenting an edge against which the ends of shingles may be laid, two clamping mechanisms attached to said member and each comprising a tongue adapted to extend beneath a laid course of 95 shingles and a roller located above the tongue and adapted to be moved bodily to different elevations relative to the tongue, substantially as described.

4. In an apparatus of the nature described, the combination of an elongated member presenting an edge against which the ends of shingles may be laid, two clamping mechanisms attached to said member and each comprising a tongue adapted 100 to extend beneath a laid course of shingles, a roller, and a roller support held for shifting in a path inclined to the upper face of the tongue, substantially as described.

5. In an apparatus of the nature described, 110 the combination of an elongated member presenting an edge against which the ends of shingles may be laid, two clamping mechanisms attached to said member and each comprising a tongue adapted to extend beneath a laid course of shingles, a roller located above each tongue, and means for bodily shifting said rollers toward and from said tongue, substantially as described.

6. In an apparatus of the nature described, 120 the combination of an elongated member presenting an edge against which the ends of shingles may be laid, two clamping mechanisms attached to said member and each comprising a tongue adapted to extend beneath a laid course of shingles, a roller located above each tongue, and means for simultaneously bodily shifting said rollers to-

ward and from said tongue, substantially as described.

7. In an apparatus of the nature described, the combination of an elongated member 5 presenting an edge against which the ends of shingles may be laid, two clamping mechanisms attached to said member and each comprising a tongue adapted to extend beneath a laid course of shingles, a roller, a 10 roller support held for shifting in a path inclined to the upper face of the tongue, and means for shifting said supports, substantially as described.

8. In an apparatus of the nature described, 15 the combination of an elongated member presenting an edge against which the ends of shingles may be laid, two clamping mechanisms attached to said member and each comprising a tongue adapted to extend beneath a laid course of shingles, a roller, a 20 roller support held for shifting in a path inclined to the upper face of the tongue, and means for simultaneously shifting said supports, substantially as described.

25 9. In an apparatus of the nature described, the combination of an elongated member presenting an edge against which the ends of shingles may be laid, clamping mechanism attached to said member and comprising 30 a tongue adapted to extend beneath a laid course of shingles, an upper clamping member adapted to bear downward, an upper clamping member support inclined to the upper face of the tongue, and means for 35 moving said inclined member endwise, substantially as described.

10. In an apparatus of the nature described, the combination of an elongated member presenting an edge against which 40 the ends of shingles may be laid, a pivoted hand lever, two clamping mechanisms attached to said member and each comprising a tongue adapted to extend beneath a laid course of shingles, an upper clamping member 45 adapted to bear downward, and an upper clamping member support inclined to the upper face of the tongue, said support being connected with the hand lever at op-

posite sides of its pivot, substantially as described.

11. In an apparatus of the nature described, the combination of an elongated member presenting an edge against which the ends of shingles may be laid, a yoke attached to said member, a tongue adapted 55 to extend beneath the last laid course of shingles, a roller located above the tongue, and a roller support which is inclined to the upper face of the tongue and shiftable endwise, substantially as described.

60 12. In an apparatus of the nature described, the combination of an elongated member presenting an edge against which the ends of shingles may be laid, a yoke attached to said member, a tongue supported 65 by said yoke and adapted to extend beneath a laid course of shingles, and a roller located above the tongue and supported by the yoke and adapted to be moved to different elevations relative to the tongue, substantially as described.

65 13. In an apparatus of the nature described, the combination of an elongated member presenting an edge against which the ends of shingles may be laid, two yokes 75 attached to said member, two tongues adapted to extend beneath the last laid course of shingles, a roller located above each tongue, and for each of said rollers, a support which is inclined relative to the upper face of the 80 tongue and is endwise shiftable, substantially as described.

14. In an apparatus of the nature described, the combination of an elongated member having an edge against which the 85 ends of shingles may be laid and a ledge upon which said shingles may rest, and a clamping mechanism attached to said member and adapted to engage the upper and lower faces of the shingles of a laid course, 90 substantially as described.

In testimony whereof I have signed my name this 25th day of November, in the year one thousand nine hundred and nineteen.

JAY HUGH JOHNSON.
